Fig. 1

Fig. 2

Fig. 3

Fig. 4

Figure 1 is a side elevational view of a shoe sole showing my new design;

Figure 2 is a bottom plan view thereof;

Figure 3 is a longitudinal sectional view thereof taken on line 3—3 of Figure 2; and

Figure 4 is a transverse sectional view of the same taken on line 4—4 of Figure 2.

The dotted line showing is merely for the purpose of illustrating the environmental use of the instant design.

I claim:

The ornamental design for a shoe sole, as shown and described.
